UNITED STATES PATENT OFFICE

WILLIAM J. O'LEARY, OF DAYTON, OHIO

ACOUSTIC APPARATUS

Application filed December 24, 1927. Serial No. 242,402.

This invention relates to electrical acoustic apparatus and is particularly concerned with electrical sound reproducers.

One object of the invention is the provision of an electrical sound reproducer which may be used for the production of sound from phonograph records, embodying a coil in a magnetic field moved by the vibrational movements of a stylus which is directly connected to it.

Another object of the invention is the provision of an electrical sound reproducer of the type mentioned, embodying a coil supporting shaft which is supported by rubber mounting means.

Other objects and advantages of the invention will be apparent from the following description and from the drawings in which—

20 Fig. 1 is a side elevation of the operating parts of the present invention;

Fig. 2 is a general view of a phonograph reproducer associated with a sound record;

Fig. 3 is a section on the line 3—3 of

25 Fig. 1;

Fig. 4 is a section on the line 4—4 of Fig. 1 showing the rubber mounting block;

Fig. 5 is a section on the line 5—5 of Fig. 1; and

30 Fig. 6 is an enlarged section through the coil.

Referring more particularly to the drawings, the electrical sound reproducer comprises a case 10 in which the operating parts 35 of the apparatus shown in Fig. 1 are mounted. This case is suitably supported upon a tone arm 11 which is adapted to rotate about the vertical axis 12 in the customary manner, the mounting of the case 10 being such that it may move vertically and 40 may be swung laterally so as to follow the movements of the record indicated at 13. This record may be of any desired type but as shown, it is of the kind in which the 45 grooves are transversely cut.

Within the case and fixed thereto by suitable screws 16 is a magnet 17. This magnet may be of any desired type effective in the production of a magnetic field, and as shown 50 in the drawings, is a permanent horse-shoe-

shaped magnet having adjacent poles 18 and 19. Between the poles is a fixed iron armature 20, so arranged as to provide two small air gaps 21 and 22 between it and the two poles of the magnet. The armature is 55 fixed in position by means of a plate 23 of brass or other suitable non-magnetic material which is attached to the armature and to the magnet by means of suitable screws 24. The plate 23 is bent to provide a seat 60 26 in which is tightly fitted a rubber mounting block 27, located adjacent the armature 20. The opposite part of the magnet is provided with a rubber block 30, tightly seated therein, and within the two blocks 27 and 65 30 are shaft receiving openings which snugly receive a shaft 31 and which are effective in yieldingly restraining movements of this shaft in any direction. The end of the shaft which rests in block 27 is preferably provided with a flat side as indicated at 32 to prevent any substantial twisting movements of the shaft in relation to the rubber block and thus maintain the normal position 70 of the shaft yieldingly. The shaft extends 75 between the rubber mounting blocks, passing through a central bore 29 in the armature of somewhat larger size than the diameter of the shaft, and supported by the shaft adjacent the poles of the magnet is a coil of 80 wire 35 preferably consisting of a number of turns passing around and supported by a brass shell 33 and spaced from the armature 20 as shown in the drawings. The shell 33 as shown in Fig. 6 is not continuous around 85 the entire coil but on the contrary is provided with a gap 34 so that a complete metallic circuit is not formed by the shell. The upper and lower ends of the shell through 90 which the shaft 31 extends are fixed to the shaft in any suitable manner. The terminal ends of the coil extend as shown at 36 so that they may be conveniently attached to electrical devices in a suitable circuit for the reproduction of sound. The coil 35 has 95 its axis corresponding with the longitudinal axis of the shaft 31 and the coil is so mounted in the magnetic field which is effective across the two air gaps 21 and 22, that when it is rotationally oscillated, elec- 100

tric currents will be generated in the coil and will flow through the terminal ends 36 to a suitable amplifying or reproducing apparatus such as an audion tube amplifier or a sound producing unit.

6 The shaft 31, as previously mentioned, is mounted at one end as indicated at 38 in the rubber block 27, and it projects through the magnet and through the rubber block 30 and at its free end is provided with a stylus holder 39. This stylus holder is rigidly fastened in any suitable way to the end of the shaft and is provided with means such as a thumb screw 40 and a receiving opening so that a stylus 41 may be mounted therein in fixed position, with the axis of the stylus somewhat displaced from the axis of the shaft 31. The shaft 31, the coil 35, the stylus holder and the stylus are all of 10 light weight and collectively provide an assembly or movable element having a small movement of inertia about the axis of the shaft 31.

15 Fixed to and depending from the magnet 25 17 is an arm 42 of such length as to engage and ride in the top of the grooves of the record in which the sound cuts are provided. The lower end of arm 42 is comparatively large and rounded so it may slide along the 20 top of the grooves without being affected by and without affecting the sound or reproducing cuts. This arm is therefore effective in guiding the tone arm thus keeping the center of shaft 31 always located in the 25 center of the groove, and also operates to relieve a part of the weight of the apparatus from the stylus. In order to play hill and dale records the apparatus is mounted at an angle of 90° from that shown in the drawings, and in that case the arm or guide 42 30 must then be placed in line with the center of the stylus.

35 As is readily seen the device is reversible in operation and variations of current in the 40 electrical transforming means may be used to produce mechanical oscillations of the stylus for cutting records from which sound may be reproduced. When used for the creation of electrical current oscillations the 45 vibrational movements of the stylus 41 as the latter operates in the transversely cut grooves of the phonograph record 13 is effective in the production of oscillations of the movable assembly formed of the shaft 50 and the parts fixed to it, and the coil is thus 55 rotationally oscillated in the magnetic field so that currents are generated in the coil which are proportional to the vibrational 60 movements of the stylus. The stylus point 65 moves in a plane which is less than 45° to the plane of the record and normal to the axis of the shaft 31, and the motion of the stylus is about an axis which is normal to a line tangential to the groove of the record.

65 As the various parts of the movable assem-

bly are all firmly attached in a rigid manner to one another there is absolutely no possibility of any lost play such as obtains where several parts are pivotally connected to one another, and in a device of this character where the actual movements are excessively slight as compared with the clearance found in a pivotal connection, the sound which is produced in the device connected to the terminals 36 of the coil will be accurate 70 reproductions of the sound waves corresponding to the grooves in the record. The shaft 31 is efficiently supported by the rubber blocks 30 and 27 so that the movable assembly of the reproducer will have no 75 fixed period of oscillation. That is, the movable assembly will not tend to continue to oscillate at any particular frequency by reason of its own torsional period of vibration. The rubber forms a support acting 80 to return the movable assembly to its normal position and yieldingly tend to hold it there against the efforts of the stylus. The manner in which the movable assembly is constructed and mounted in place provides for 85 ease in construction and cheapness in manufacture and avoids delicate pivotal mountings and delicate springs, and avoids torsional vibrational periods of oscillation always present when such springs are employed.

90 While the form of apparatus herein described constitutes a preferred embodiment of the invention, it is to be understood that the invention is not limited to this precise 95 form of apparatus, and that changes may be made therein without departing from the scope of the invention which is defined in the appended claims.

100 What is claimed is:

105 1. An electrical sound reproducer for phonographs comprising a magnet, a coil rotatably mounted in the field of the magnet, a shaft on which said coil is fixed with the axis of rotation of the coil coinciding 110 with the axis of the shaft, a rubber block mounted in said magnet, and snugly receiving said shaft to mount the shaft for rotational oscillations, a rubber mounting block supporting one end of the shaft adjacent 115 said coil, and a stylus holder fixed to the other end of said shaft and adapted to receive a stylus with its axis displaced from the axis of the shaft, whereby oscillations of the stylus are transmitted through said shaft to the coil to cause the generation of currents in the coil.

120 2. An electrical sound reproducer for phonographs comprising a permanent magnet, a coil rotatably mounted in the field of the magnet, a fixed iron armature within 125 said coil, a shaft on which said coil is fixed with the axis of rotation of the coil coinciding with the axis of the shaft, a rubber mounting block mounted in said magnet,

and snugly receiving said shaft to mount the shaft for rotational oscillations, a rubber mounting block supporting one end of the shaft adjacent said coil, said blocks providing the sole means for urging the shaft and the coil to a normal position, and a stylus holder fixed to the other end of said shaft and adapted to receive a stylus with its axis displaced from the axis of the shaft, whereby oscillations of the stylus are transmitted through said shaft to the coil to cause the generation of currents in the coil.

3. In a device of the class described, the combination of a permanent magnet with opposed pole pieces, a stationary armature mounted between said pole pieces to provide a pair of air gaps, said air gaps comprising sections of a tubular space formed by concave faces on the poles of the magnet and convex faces on the armature, a shaft extending through said armature with the axis of the said shaft coinciding with the axis of said tubular space, a coil of insulated wire mounted upon said shaft and with the sides of said coil extending through said air gaps, resilient means for supporting said shaft to permit slight torsional movements thereof, and a stylus carried by said shaft whereby said shaft is oscillated when said stylus cooperates with a groove of a moving phonograph record.

4. In a device of the class described, the combination of a permanent magnet with opposed pole pieces, a stationary armature carried by said magnet and mounted between said pole pieces to provide a pair of air gaps, said air gaps comprising sections of a tubular space formed by concave faces on the poles of the magnet and convex faces on the armature, a shaft extending through said armature with the axis of the said shaft coinciding with the axis of said tubular space, a coil of insulated wire mounted upon said shaft and with the sides of said coil extending through said air gaps, resilient rubber bearings carried by said magnet for supporting said shaft to permit slight torsional movements thereof, means tending to normally resist said torsional movements, and a stylus carried by said shaft whereby said shaft is oscillated when said stylus cooperates with a groove of a moving phonograph record.

5. A device of the class described comprising in combination a permanent magnet in the form of a broken ring with the poles of said magnet opposed to each other, a stationary armature mounted between said poles to provide a pair of narrow air gaps, a shaft having the axis thereof substantially midway between said air gaps, a coil carried by said shaft and extending through said air gaps, a resilient thrust bearing on the upper end of said shaft, and a resilient torsional bearing for the lower portion of

said shaft, and a stylus carried by said shaft in such manner as to cause oscillatory movements to said shaft when said stylus is properly associated with a groove of a moving phonograph record.

6. A device of the class described comprising in combination a circular permanent magnet in the form of a broken ring with the poles of said magnet opposed to each other, a stationary armature mounted between said poles to provide a pair of narrow air gaps, a shaft having the axis thereof substantially midway between said air gaps, a coil carried by said shaft and extending through said air gaps, a resilient rubber thrust bearing enclosing and supporting the upper end of said shaft, and a resilient rubber torsional bearing for the lower portion of said shaft, and a stylus carried by said shaft in such manner as to cause oscillatory movements to said shaft when said stylus is properly associated with a groove of a moving phonograph record.

7. In a device of the class described, in combination a magnet having opposed pole pieces, a shaft located in substantially the mid distance between said pole pieces, a coil of insulated wire carried by said shaft in such manner that the lines of force from said pole pieces cut two sides of said coil, a resilient thrust bearing for the upper end of said shaft, and a resilient torsional bearing for the lower portion of said shaft, means to normally resist twisting of said shaft and to tend to hold said coil in position between said pole pieces, and means for rotatably oscillating said shaft when said last mentioned means cooperates with the groove of a moving phonograph record.

8. In a device of the class described, in combination a magnet having opposed pole pieces, a shaft located in substantially the mid distance between said pole pieces, a coil of insulated wire carried by said shaft in such manner that the lines of force from said pole pieces cut two sides of said coil, a resilient thrust bearing for the upper end of said shaft, said thrust bearing being carried by said magnet, and a resilient torsional bearing for the lower portion of said shaft, said thrust bearing being mounted in said magnet, means to normally resist twisting of said shaft and to tend to hold said coil in position between said pole pieces, and means for rotatably oscillating said shaft when said last mentioned means cooperates with the groove of a moving phonograph record.

9. An electrical pick-up unit for phonographs comprising in combination a permanent magnet of substantially circular form with opposed pole pieces, a shaft extending between said pole pieces, a coil mounted upon said shaft, a thrust bearing for said shaft carried by said magnet, and

a tortional bearing for said shaft carried by said magnet, whereby said magnet comprises a main frame for the operating parts of said unit.

- 5 10. An electrical pick-up unit for phonographs comprising in combination a magnet with opposed pole pieces, a shaft extending between said pole pieces, a coil mounted upon said shaft and having opposite sides
10 between said pole pieces, a thrust bearing for said shaft carried by said magnet, and a tortional bearing for said shaft carried by said magnet, whereby said magnet comprises a main frame for the operating parts of said unit.

15 In testimony whereof I hereto affix my signature.
